UNITED STATES PATENT OFFICE.

LEWIS P. HALLADAY, OF DECATUR, ILLINOIS.

POLISHING MACHINE.

Application filed May 12, 1924. Serial No. 712,532.

My invention relates to improvements in polishing machines and has for one object to provide a new and improved form of machine for polishing or buffing automobile bumper bars or the like or any similar elongated piece of work wherein it is necessary to polish or buff long narrow exposed surfaces. Another object of my invention is to provide a polishing machine wherein the 10 polishing operation may be continuous on a series of pieces of work successively and simultaneously going through the machine. Another object of my invention is to provide means for changing and renewing the 15 polishing elements without interfering with the operation of the machine. Another object is to provide a machine wherein pieces to be polished may be fed in and taken out as the work is done without interfering 20 with the work on the balance of the pieces. Other objects will appear from time to time in the specification and claims.

My invention is illustrated more or less diagrammatically in the accompanying drawings, wherein—

Figure 1 is a side elevation of the feed end of the machine;

Figure 2 is a side elevation of the continuation of Figure 1 showing the discharge 30 end of the machine;

Figure 3 is a side elevation on an enlarged scale showing details;

Figure 4 is a plan view showing one of the polishing elements;

Figure 5 is a section along the line 5—5 of Figure 3 on an enlarged scale;

Figure 6 is a section on an enlarged scale along the line 6—6 of Fig. 3 showing parts in elevation;

Figure 7 is a detail on a larger scale of a part of the showing in Figure 6;

Figure 8 is a plan view of the end of the track;

Figure 9 is a side elevation of parts shown in Figure 8;

Figure 10 is a section along the line 10—10 in Figure 8;

Like parts are indicated by like characters throughout.

A is a head end bearing frame, A¹ a tail end bearing frame, A² a work track, A³ a return track interposed between the frames A A¹. A⁴ is a driving sprocket on the head end bearing frame A, A⁵ a tail sprocket on the tail end bearing frame A¹. A⁶ is an endless chain traveling about the sprockets

A⁴ A⁵ and riding on the tracks A² A³. This chain carries the work on its upper range along the work track A² and returns empty on the lower return track A³. The 60 track A² is in line with the sprockets A⁴ A⁵ being just slightly below the pitch line thereof. The track A³ is bent upwardly at its ends and comes outside the pitch line of the sprockets A⁴ A⁵ and has extensions A¹⁶ 65 extending upwardly into line with the track A² on the opposed sides of the sprockets A⁴ A⁵ to more effectively guide the chain. The track A³ is made up of two separate 70 T rails having the web downwardly extended. It is mounted on brackets A⁷ on the frames A A¹ and on U brackets A⁸ projecting outwardly from the frames A⁹. These frames are spaced along the track between the frames A A¹. These frames also carry 75 the T-rails forming the track A², there being brackets A¹⁰ on the frames A⁹ to carry them. There is thus clearance between the two elements of the track A² so that the 80 downwardly depending parts of a chain may pass between the two elements of the track.

Referring to Figures 8, 9 and 10, particularly, B is a drive shaft carried in bearings B¹ on the frame A. This drive shaft is 85 square and slidably engages the sprocket A⁴ which is held against rotation thereon. B² is a sprocket keyed to the shaft B driven by means of a sprocket chain B³ through a reduction gear B⁴ from the motor B⁵. Rotation of this shaft and sprocket drives 90 the chain A⁶ which travels along the tracks A² A³. B⁷ is a slotted drum associated with the sprocket A⁴. The slot on this drum is rotatably engaged by a fork B⁸ which fork projects from a web plate B⁹ which ties the 95 two T-rails forming the track A² together at their ends and limits inward movement of the sprocket with respect to the track, thus correctly positioning the sprocket and the track. The arrangement is the same at the 100 other end except that there is no provision is made for applying power to the tail shaft.

The chain A⁶ may be made up of any suitable form of link belt and carries a series of carriages C having four rollers C¹ C¹ 105 flanged to ride, two of them along each of the track forming rails. These carriages are closely spaced in pair on the chain, there being between them two roller carriages C² having rollers C³ each engaging one of the 110 track elements. These two roller carriages are held against rotation by the chain and

- have upwardly projecting struts C⁴ thereon. As the carriages C are disposed upon the chain, the front carriage of each pair is the following carriage, the rear carriage, the leading carriage with reference to the work supported thereby. Each leading carriage has a lug C⁵ projecting upwardly therefrom. Projecting at right angles from this lug and spaced above the carriage is a holding bar C⁶. Associated with the holding bar and spaced forwardly from it is a holding finger C⁷ and at the end of the bar is a forwardly projecting lug C⁸. C⁹ is the work taking in this case the form of a spring steel auto-
 15 mobile bumper impact bar having its ends bent in a kind of shepherd's crook arrangement, the loop thus formed engages the bar C⁸ passing under the finger C⁷ which holds it against forward movement and located at
 20 one side of the lug C⁸ which holds it against lateral movement. Obviously this bumper bar is free to rotate on the holding bar and when introduced from an angle to the rear, its edge can be placed between the bar or pin
 25 and finger and when it is rotated into parallelism with the chain, it drops down to one side of the lug and is held in place. Each of the following carriages C has two upwardly projecting fingers C¹⁰, one on either
 30 side. If the work is raised up at the rear end, it can be swung into line with these fingers, then dropped down between them and in this position is rotated to travel along the train and be worked upon. It is held against
 35 longitudinal displacement by the leading carriage and against lateral displacement by the following carriage. The bar also rests intermediate its ends upon the struts C⁴ projecting upwardly from the two roller carriages and is free to move laterally along them and also along the following carriage as it bends or gives under the influence of the buffering wheel which does the work. As
 40 above suggested, the struts C⁴, the fingers C¹⁰ and the lugs C⁵ are free to travel between the two track elements on the return path hanging down between them as indicated in Figure 3. The chain is so attached to these carriages that they ride around the sprockets at both ends with the chain without interference and the extensions A¹⁶ on the lower track guide the carriages around the sprockets so as to avoid any undue interference or jerking or displacement of parts.
 45 The track A² is made up as previously indicated of a pair of parallel T-trails with the web downwardly depending. These webs are joined together by spacing bars D which are bolted between the rail webs by
 50 means of bolts D¹ which also hold roller brackets D², one on either side of the track in place with respect thereto. These brackets have rollers D³ adapted to travel along the upper surface of the brackets A¹⁰ in a
 55 direction perpendicular to the axis of the track. D⁴ is an eccentric shaft extending along the entire length of the track A² and journaled on the frames A⁹. This eccentric shaft carries spaced therealong a plurality of eccentrics D⁵ which carry eccentric rods 70 D⁶ pivoted to ears D⁷ on the track A² so that rotation of the eccentric shaft causes the entire track A² to move back and forth perpendicular to its axis as a unit. This eccentric shaft is rotated in unison with the 75 rotation of the drive shaft B at a relatively low rate so that the lateral movement of the track is gradual but continuous back and forth during operation.
 60 Mounted on each of the frames A⁹ are A-frames E on which are journaled the buffer frames E¹. These buffer frames are stiffened by cross ribs E² E² and are provided at their outer free ends with bearings E⁴ carrying a buffer shaft E⁵. Intermediate the 85 bearings E⁴ keyed to each shaft E⁵ is a belt pulley E⁶. E⁷ E⁷ are buffer wheels removably mounted on each of the shafts E⁵ and overlying the chain, track and work. E⁸ is a motor located between the frames E 90 concentric with the axis of rotation of the frame E¹ and provided with a belt wheel E⁹ driving a belt E¹⁰ which travels over the pulley E⁶.
 95 F is a C-bracket projecting upwardly from the frame A⁹ and supported at its free end by a strut F¹, just in front of the A-frames E. F² is a counter-balance lever pivoted on the bracket F. It is engaged at its free end by the bail F³ on the frame E¹ and projects rearwardly beyond the motor E⁸ at F⁴ to carry a counter-balance weight F⁵ and supporting rod F⁶. This counter-balance weight is so arranged as to permit the grinding or buffering head or wheel to press 100 downwardly on the work with about twenty-five pounds pressure. F⁷ is a push rod pivoted on the frame E¹ adjacent its free end and carried by a latch lever F⁸ pivoted on the frame A⁹ having a foot pedal F¹⁰. This 105 lever is loosely pivoted and may be swung sideward when depressed to engage a latch F¹¹ so as to hold the buffering wheel out of contact with the work until the latch is released.
 110 G is an air duct supported on the brackets F discharging into the suction fan G¹ driven by a belt from any suitable source of power applied to the pulley G². This fan discharges dust laden air to any suitable separating means not here shown. G³ G³ are flexible pipes communicating at one end with the duct G and at the other end with the housings G⁴ enclosing the buffering wheels E⁷. These housings G⁴ have pivoted doors G⁵ 115 which may be swung aside to gain access to the buffering wheels when it is desired to renew them. G⁶ G⁶ are adjustable stops limiting the downward movement of the buffering wheels under the influence of the twenty-
 120

five pounds pressure above referred to so as to prevent these wheels dropping too far down between their engagement with successive pieces of work. The engagement of the fork B^s projecting from the track with the drum B' insures that as the track moves laterally the drum, sprocket, and chain will travel with it causing the drum and sprocket to slide on the squared shaft without interfering with the drive of the chain.

It will be evident that while I have shown in my drawings, an operative device, still many changes might be made in the size, shape and arrangement of parts without departing materially from the spirit of my invention. I wish, therefore, that my showing be taken as in a sense diagrammatic.

The use and operation of my invention are as follows:

20 With the chain in operation moving forward along its working track and with the separate motors each driving separately a buffing wheel and with the working track oscillating in a direction perpendicular to its axis and with the suction fan at work ready to carry away the dust from the buffing wheels, the apparatus is ready for operation.

The operator at the tail end of the chain 30 will pick up successive bumper bars or other pieces of work holding them at an angle to the axial line of the track, he will engage the front loop on the bumper bar beneath the guide hook, will then swing the bumper bar 35 in line with the chain bringing the hook thereon behind the lug on the holding bar. He then lowers the work so that the rear end rests on the rear carriage between the two upwardly projecting lugs. The work is 40 positively but loosely held in position free to move longitudinally and to give with the chain and with the progress of the work, the bar being supported intermediate its ends by the upwardly projecting struts. This engagement is made while the chain is moving 45 forward. As the chain goes forward it carries this bar under successive rotating buffing wheels. The wheels ride up around the curved end of the bumper bar at the 50 front end, pass along the impact face and at the end drop down being limited in downward movement by the adjustable stops. Each successive buffing wheel thus works on the entire length of the bar. The bar as it 55 passes along is moved back and forth in a direction perpendicular to its axis across the face of the wheel. This gives even wear of the wheel and even polishing of the bar. The dust from the buffing action is drawn 60 into the hood surrounding the wheel by the inrush of air and thence through the dust catching system. At the head end of the chain an operator reverses the process and takes the bumper bar or other work off the chain, leaving the chain to go down under-

neath on the fixed return track. There is sufficient flexibility in the chain so that the return track does not need to vibrate in unison with the upper or working track.

The buffing wheels wear away rapidly and the operators manipulate the stops to insure that as the wheels wear they will always be allowed to come down far enough to properly engage the work. The operators also during the running of the machine are constantly engaged in changing the worn buffer wheels and replacing them with new wheels. As shown, there are ten wheels. Eight are enough to do the work so that two wheels can be out of commission at all times being 75 replaced. The operator replaces a wheel by putting his foot on the latch lever, rotating the buffing frame up about its axis, swinging the lever under the stop to lock the wheel out of contact. He then stops the motor, 80 swings open the door on the air hood, unscrews the nut which holds the wheel in place, removes it, inserts a new wheel, closes the door, starts the motor, adjusts the stop, releases the latch and the wheel is again in 85 operation. Since all these adjustments and changes are made on single wheels one at a time without interfering with the operation leaving enough wheels in action to do satisfactory buffing, the work is continuous and 90 buffed bumper bars or other work are fed constantly through the machine and discharged at the head end in a finished condition so far as this particular machine is concerned.

100 In my claims I have used the terms grinding machine and grinding wheel in the broadest sense of the word. The invention is primarily intended for buffing or polishing and the wheels are normally canvas or fabric buffing or polishing wheels. Buffing and polishing is a grinding action and it is obvious that the buffing wheel is a grinding wheel in the broad sense of the word because it does grind as it polishes.

110 I claim:

1. In a grinding machine, a pivot frame, a grinding wheel rotatably mounted thereon, a motor carried thereby, a driving connection between it and the wheel, means for giving the wheel and work relative movement in a direction tangent to the wheel, means for adjustably limiting the downward movement of the wheel in the direction of the work, means for raising the wheel out of engagement with the work and for locking it in inoperative position, said means comprising a push rod pivoted to one end of the frame and a lever pivoted at the other end of the push rod and a stop adapted to be brought into engagement with the lever to lock the push rod and lever in raised position.

115 2. In a grinding machine, a plurality of spaced grinding wheels, means for feeding 120

- work continuously into working engagement with each of said wheels in succession, said means comprising an endless chain upon which the work is mounted, means for yieldingly holding the wheels against the work and means for limiting the movement of the wheels toward the work between engagement with successive pieces of work, means for moving the work laterally during its feed 10 toward and past the wheels.
3. In a grinding machine, a track, means for reciprocating it in a direction perpendicular to its longitudinal axis, a chain and means for propelling it laterally therealong, 15 work carrying means adapted to be propelled along the track by the chain and a plurality of separate grinding wheels arranged along the track and adapted to successively engage successive pieces of work.
4. In a grinding machine, a track, means for reciprocating it in a direction perpendicular to its longitudinal axis, a chain and means for propelling it laterally therealong, work carrying means adapted to be propelled 20 along the track by the chain and a plurality of separate grinding wheels arranged along the track and adapted to successively engage successive pieces of work, a return track for the chain approximately in line with the 25 reciprocating track and held against reciprocation.
5. In a grinding machine, a track, means for reciprocating it in a direction perpendicular to its longitudinal axis, a chain and means for propelling it laterally therealong, work carrying means adapted to be propelled 30 along the track by the chain and a plurality of separate grinding wheels arranged along the track and adapted to successively engage successive pieces of work, supporting brackets for the track arranged perpendicular to the axis thereof and rollers 35 interposed between the track and the brackets.
6. In a grinding machine, a track, means for reciprocating it in a direction perpendicular to its longitudinal axis, a chain and means for propelling it laterally therealong, work carrying means adapted to be propelled 40 along the track by the chain and a plurality of separate grinding wheels arranged along the track and adapted to successively engage successive pieces of work, the propelling means comprising a drive shaft, a chain sprocket 45 slidable thereon and held against rotation thereby and means interposed between the reciprocating track and the sprocket for imparting the reciprocating movement of the track to the sprocket.
7. In a grinding machine, a track, means for reciprocating it in a direction perpendicular to its longitudinal axis, a chain and means for propelling it laterally therealong, 50 work carrying means adapted to be pro-
- pelled along the track by the chain and a plurality of separate grinding wheels arranged along the track and adapted to successively engage successive pieces of work, the propelling means comprising a drive 70 shaft, a chain sprocket slidable thereon and held against rotation thereby and means interposed between the reciprocating track and the sprocket for imparting the reciprocating movement of the track to the sprocket, 75 said means comprising a forked element mounted on the track rotatably engaging the sprocket.
8. In a grinding machine, a track, means for reciprocating it in a direction perpendicular to its longitudinal axis, a chain and means for propelling it laterally therealong, work carrying means adapted to be propelled 80 along the track by the chain and a plurality of separate grinding wheels arranged along the track and adapted to successively engage successive pieces of work, the reciprocating means comprising an eccentric shaft parallel with the track and a plurality of eccentrics thereon spaced along 85 the track, connections between the track and the eccentrics whereby the track is given a parallel movement throughout its entire length.
9. In a grinding machine, a track, means 90 for reciprocating it in a direction perpendicular to its longitudinal axis, a chain and means for propelling it laterally therealong, work carrying means adapted to be propelled along the track by the chain and a plurality of separate grinding wheels arranged along the track and adapted to successively 95 engage successive pieces of work, supporting brackets for the track arranged perpendicular to the axis thereof and rollers 100 interposed between the track and the brackets.
10. In a grinding machine, a track, means for reciprocating it in a direction perpendicular to its longitudinal axis, a chain and means for propelling it laterally therealong, work carrying means adapted to be propelled 110 along the track by the chain and a plurality of separate grinding wheels arranged along the track and adapted to successively engage successive pieces of work, the propelling means comprising a drive shaft, a chain sprocket slidable thereon and held against rotation thereby and means interposed 115 between the reciprocating track and the sprocket for imparting the reciprocating movement of the track to the sprocket, supporting brackets for the track arranged perpendicular to the axis thereof and rollers 120 interposed between the track and the brackets.
11. In a grinding machine, a track, supporting brackets therefor perpendicular thereto, rollers interposed between them, sprockets associated with either end of the 125

- bracket held against transverse movement with respect to the track, a chain travelling along the track and over the sprockets and means for imparting reciprocation to the track in a direction perpendicular to its axis.
12. In a grinding machine, a track, supporting brackets therefor perpendicular thereto, rollers interposed between them, sprockets associated with either end of the track held against transverse movement with respect to the track, a chain travelling along the track and over the sprockets and means for imparting reciprocation to the track in a direction perpendicular to its axis, a return track for the chain independent of the reciprocating track having extensions projecting upwardly around the sprockets.
13. The combination with a track of a plurality of work supporting carriages adapted to travel therealong, one having a transverse holding pin with a hook parallel to and in front of it and a lug projecting forward from the other end of it, another having a pair of upwardly projecting spaced lugs and an intermediate carriage having an upwardly projecting work supporting lug and a chain to hold the carriages in fixed relation and propel them along the track.
14. The combination with a track of a plurality of work supporting carriages adapted to travel therealong, one having a transverse holding pin with a hook parallel to and in front of it and a lug projecting forward from the other end of it, another having a pair of upwardly projecting spaced lugs and a chain to hold the carriages in fixed relation and propel them along the track.
15. The combination with a track of a plurality of work supporting carriages adapted to travel therealong, one of them having means to engage loosely and hold the work against longitudinal and angular displacement, the other having means to hold the work while permitting longitudinal but preventing lateral displacement and a chain to hold the carriages in fixed relation and propel them along the track.
16. The combination with a track of a plurality of work supporting carriages adapted to travel therealong, one of them having means to engage loosely and hold the work against longitudinal and angular displacement, the other having means to hold the work while permitting longitudinal but preventing lateral displacement and a chain to hold the carriages in fixed relation and propel them along the track and an intermediate carriage having an upwardly projecting work supporting lug.
17. In a transmission, a supporting track and a drive shaft rotatable therein, a sprocket free to slide longitudinally thereon and held against rotation with respect thereto, a track at right angles to the shaft and means for moving it laterally, a connection between the track and sprocket whereby the sprocket moves along the shaft in unison with the track and a chain travelling along the track and over the sprocket.
18. In a transmission, a supporting track and a drive shaft rotatable therein, a sprocket free to slide longitudinally thereon and held against rotation with respect thereto, a track at right angles to the shaft and means for moving it laterally, a connection between the track and sprocket whereby the sprocket moves along the shaft in unison with the track and a chain travelling along the track and over the sprocket, a return track fixed in position and adapted to receive the chain from the sprocket at all positions of the movable track and sprocket.
19. In a transmission, a supporting track and a drive shaft rotatable therein, a sprocket free to slide longitudinally thereon and held against rotation with respect thereto, a track at right angles to the shaft and means for moving it laterally, a connection between the track and sprocket whereby the sprocket moves along the shaft in unison with the track and a chain travelling along the track and over the sprocket, the connection between the track and sprocket comprising a peripherally slotted drum associated with the sprocket and a fork carried by the track and rotatably engaging the slot in the drum.
20. In a grinding machine, a track, a chain movable longitudinally thereon, a series of carriages propelled by the chain along the track and means on the carriages for holding separate pieces of work at one end, the free end of the work being free to move longitudinally but held against angular displacement.
21. In a grinding machine, a track, a chain movable longitudinally thereon, a series of carriages propelled by the chain along the track and means on the carriages for holding separate pieces of work at one end, the free end of the work being free to move longitudinally but held against angular displacement, and means intermediate the ends of the work associated with the chain for supporting the work at spaced points throughout its length.
22. In a grinding machine, a track, a plurality of grinding wheels arranged therealong, means for conveying work along the track into engagement with successive wheels and means for moving the track and work laterally across the faces of the wheels in unison with the longitudinal movement of the work.
23. In a grinding machine, a track, a plurality of grinding wheels arranged therealong, means for conveying a continuous series of successive pieces of work along the

track into engagement with successive wheels and means for moving the track and work laterally across the faces of the wheels in unison with the longitudinal movement of the work.

24. In a grinding machine, a track, a plurality of grinding wheels arranged therealong, means for conveying work along the track into engagement with successive wheels and means for moving the track and work laterally across the faces of the wheels in unison with the longitudinal movement of the work and manually controlled means for holding selected grinding wheels out of operative relation with the work independent of the operation of the balance of the machine.

25. In a grinding machine, a track, a plurality of grinding wheels arranged therealong, means for conveying a continuous series of successive pieces of work along the track into engagement with successive wheels and means for moving the track and work laterally across the faces of the wheels in unison with the longitudinal movement of the work, and manually controlled means for holding selected grinding wheels out of operative relation with the work independent of the operation of the balance of the machine.

Signed at Chicago, county of Cook and State of Illinois, this 9th day of May, 1924.

LEWIS P. HALLADAY.
